UNITED STATES PATENT OFFICE.

LOUIS J. NORTHERN, OF ROBINSON, KANSAS.

HORSESHOEING DEVICE.

SPECIFICATION forming part of Letters Patent No. 735,288, dated August 4, 1903.

Application filed March 30, 1903. Serial No. 150,214. (No model.)

To all whom it may concern:

Be it known that I, LOUIS J. NORTHERN, a citizen of the United States, residing at Robinson, in the county of Brown and State of Kansas, have invented certain new and useful Improvements in Horseshoeing Devices; and I do declare the following to be a full, clear, and exact description of the invention, such as will enable others skilled in the art to 10 which it appertains to make and use the same.

This invention relates to holding devices to aid in shoeing horses.

The object of this invention is to provide a device of this character by which a shoe 15 may be firmly held in place while being nailed to the hoof.

Another object is to provide a holder of this character which will also serve as a shield or covering for the point of the nails as they 20 are driven through the hoof, thereby preventing the same from doing any damage should the horse jerk his foot away before the nails have been clenched.

A further object is to provide a device of this character which will be simple in construction, strong and durable, quickly attached and removed, and well adapted to the 25 use for which it is designed.

With these and other objects in view the 30 invention consists of certain novel features of construction, combination, and arrangement of parts, as will be hereinafter more fully described, and particularly pointed out in the appended claims, reference being had 35 to the accompanying drawings, in which—

Figure 1 is a view of the lower end of a horse's leg and hoof, showing the application of the device. Fig. 2 is a side view of the device detached. Fig. 3 is a top plan view of 40 the same, showing the parts closed in full lines and in open position in dotted lines.

In the drawings, 1 denotes the clamp, comprising two segmental-shaped plates 2 and 3, hinged together at their forward ends. On 45 the inner edges of each of the plates 2 and 3 are formed shields or guard-plates 4, which are curved upwardly and adapted to fit and engage the sides of the hoof. The rear ends of the guards or shields 4 taper downwardly 50 and are formed into downwardly-projecting arms 5, on the lower ends of which are formed inwardly-projecting lugs 5^a, which are adapt-

ed to engage the heels or heel-calks of the shoe.

7 denotes a stiff curved spring, one end of 55 which is pivoted to the segmental plate 2, and the opposite end of which is pivoted to a cam-lever 8, which has a pivotal engagement with the plate 3 in such manner that when the free end or handle of the lever is pulled in 60 toward the side of the clamp the plates will be drawn together to engage the hoof and hold the clamp in place.

9 denotes a vertically-disposed spring-arm connected at its upper end to the pivot-bolt 65 of the plates 2 and 3 and having formed on its lower end an inwardly-turned hook, which is adapted to engage the toe or toe-calk of the shoe.

In practice after the shoe has been fitted 70 to the hoof the clamp is opened and applied to the hoof in position to allow the lugs on the ends of the arms 5 to engage the heel-calks and the hooked end of the arm 9 to engage the toe-calk of the shoe. The cam-lever 75 is then operated to clamp the sides tightly against the hoof to hold the device in place. The nails may all now be quickly and easily driven. The points of the same coming through the hoof behind the shield or guard- 80 plates 4 cannot become caught in the blacksmith's knee or leg should the horse jerk his foot away, and instead of upsetting and clenching each nail as it is driven and as is usually done all of the nails are driven and then 85 clenched, which is a great saving of time and labor. Furthermore, after the shoe has been fitted the clamp will securely hold the same in the proper position and prevent slipping.

A further advantage derived from the use 90 of the clamp is that the plates 4 serve as braces and relieve the foot of considerable of the jar occasioned by the driving of the nails through the hoof.

From the foregoing description, taken in 95 connection with the accompanying drawings, the construction and operation of the invention will be readily understood without requiring a more extended explanation.

Various changes in the form, proportion, 100 and the minor details of construction may be resorted to without departing from the principle or sacrificing any of the advantages of this invention.

Having thus described my invention, what I claim, and desire to secure by Letters Patent, is—

1. Means for holding horseshoes in place while being nailed to the hoof, comprising a member to engage the hoof above the tread thereof and provided with means to engage the shoe and hold it pressed against the tread of the hoof, leaving the shoe fully exposed for the driving of the nails, substantially as described.
2. Means for holding horseshoes in place while being nailed to the hoof, comprising a member adapted to engage the hoof above the tread thereof, and provided with means for pressing the shoe in contact with the tread, and with guards to shield the projecting points of the nails.
3. Means for holding horseshoes in place while being nailed to the hoof, comprising a member adapted to engage the hoof above the tread thereof and having downwardly-projecting portions to engage the calks of the shoe and to hold the shoe in contact with the hoof-tread, leaving it fully exposed for the driving of the nails, substantially as described.
4. Means for holding horseshoes in place while being nailed to the hoof, comprising a pair of plates pivotally connected and adapted to engage the hoof above the plane of the tread thereof, said plates having portions pro-

jecting downward to engage the shoe and hold it in contact with the tread of the hoof, and means for contracting and expanding the plates, substantially as described.

5. Means for holding horseshoes in place while being nailed to the hoof, the same comprising a shoe-holder adapted to be clamped to the hoof above the tread thereof and having guards to shield the projecting ends of the nails and holding members projecting downward to engage the shoe and press the same in contact with the tread of the hoof, leaving the shoe fully exposed for the driving of the nails, substantially as described.

6. Means for holding horseshoes in place while the nails are being driven, comprising segmental sections pivotally connected and provided with means to hold the shoe pressed in contact with the tread of the hoof, a spring connected at one end to one of said sections, and a cam-lever pivoted to the other section and connected to the opposite end of the spring, whereby the sections may be contracted and expanded to fit different hoofs, substantially as described.

In testimony whereof I have hereunto set my hand in presence of two subscribing witnesses.

LOUIS J. NORTHERN.
